UNITED STATES PATENT OFFICE.

GEORGE MARIE CAPELL, DECEASED, LATE OF PASSENHAM, NEAR STONY STRATFORD, ENGLAND; BY ROBERT ALFRED BLAKE, OF LONDON, ENGLAND, AND KATHLEEN MARIE DAWES, COMMONLY CALLED CAPELL, OF ST. LAWRENCE, ISLE OF WIGHT, ENGLAND, LEGAL REPRESENTATIVES.

CENTRIFUGAL FAN.

Application filed September 9, 1922. Serial No. 587,129.

To all whom it may concern:

Be it known that GEORGE MARIE CAPELL, deceased, subject of the King of Great Britain, late residing at Passenham, near Stony Stratford, in the county of Bucks, England, has invented new and useful Improvements in Centrifugal Fans, of which the following is a specification.

This invention relates to centrifugal fans and is a development of the invention described in the specifications of G. M. Capell's prior Patent No. 991134 and patent application Serial No. 498095, whereby an increased efficiency is obtained.

In these prior inventions certain main vanes curved in the direction of rotation are described, each followed by a tail blade, curved contrary to the direction of rotation and leaving a divergent space, to which air has access in the fan of 991134 from the front or back of the main vane through a passage provided by what is therein termed a porthole covered by a bent away portion of the main vane or tail blade; and in the fan of 498095 is described how a following intermediate vane may be arranged to cause impelled air to impinge upon the rear surface of the tail blade and assist the rotation of the fan wheel.

Now according to the present invention, a fan, tests of which have proved to have a greater efficiency than either of the above described constructions, has vanes and blades arranged as follows:

The main vane, curved in the direction of rotation and extending into the area of the eye or inlet circle, where it may be provided with a scoop wing, is followed by a tail blade curved contrary to the direction of rotation, to the divergent space between which tail blade and main vane air flows by a passage leading from the front of the main vane, and behind the tail blade is located an intermediate short vane curved in the direction of rotation extending from the periphery partway to the eye of the fan.

The intermediate vane is of oppositely directed curvature to that of the tail blade situated in advance thereof. This intermediate vane, by the convergence of its outer end towards the outer end of the tail blade, provides a constriction in the passage between same whereby any tendency to the

formation of a vacuum at the periphery of the wheel behind the tail blade is balanced by the plenum of fluid delivered by the intermediate vane. The passage interrupting the main vane permits air to pass from the front of the main vane to the region of reduced pressure induced by the centrifugal action in the divergent space between the main vane and tail blade.

In a modification the main vane is further interrupted, the innermost scoop portion being set back relatively to the direction of rotation and relatively to and overlapping the more outward portions thereof, so that the scoop portion of the main vane delivers air to impinge against the back of the tail blade. Also each intermediate vane may be duplicated with their inner borders progressively remoter from the eye of the fan.

Two examples of centrifugal fan wheels according to the present invention are illustrated on the accompanying drawing in which:

Fig. 1 is a side elevation, partly in section, and

Fig. 2 is a transverse section of one example.

Fig. 3 is a side elevation, partly in section of the other example.

The direction of rotation is shown by the arrows.

Referring more particularly to Figs. 1 and 2: *a a* are the side plates and *b* the eye of the fan wheel. Extending between the side plates *a* and from the periphery of the wheel into the eye *b*, are forwardly curved main vanes *c¹*, *c²* provided within the eye *b* with scoop wings *d*.

Each main vane *c¹*, *c²* is backed by a tail blade *e*, springing from the back thereof and divergent therefrom, being curved in the direction contrary to the rotation and extending to the periphery of the wheel.

Each main vane *c¹*, *c²* is interrupted by a passage *f* permitting the flow of air from the front of the inner portion *c²* of the main vane to the divergent space between the outer portion *c¹* thereof and its following tail blade *e*.

Behind each tail blade *e* is an intermediate vane *g*, curved in the direction of rotation, and extending from the periphery of the wheel partway to the eye *b*. This inter-

mediate vane g supplies a plenum of air at the periphery of the wheel to the back of the respective tail blade e which balances any tendency to the formation of a vacuum at the back of the tail blade which would set up a peripheral inrush of air.

The construction shown in Fig. 3 differs from that shown in Figs. 1 and 2 in so far as each main vane is divided, an innermost portion c^3 bearing the scoop wing d being set back and overlapping the more outward portions c^1 and c^2 . This innermost portion c^3 of the main vane delivers air directly to impinge against the back of the respective tail blade e .

Also each intermediate vane is duplicated, there being two intermediate vanes g^1 , g^2 , of which the inner border of the more rearwardly g^2 is remoter from the eye b than the inner border of the forward intermediate vane g^1 of each pair, which latter assists in impelling air against the rear surface of the respective tail blade e .

The inner border of the middle portion c^2 of the main vane illustrated in Fig. 3 is indicated by dot dash lines x in Fig. 2.

A plurality of intermediate vanes g may be provided instead of one in the fan according to Fig. 1, moreover such plurality may, both in the fan according to Fig. 3 as well as in the fan according to Fig. 1, exceed two intermediate vanes.

We claim:—

1. In a centrifugal fan, an apertured main vane curved in the direction of rotation extending from the periphery into the eye of said fan, a tail blade curved contrary to the direction of rotation extending from the periphery and contacting with said main vane and located behind the aperture in said main vane, and an intermediate short vane curved in the direction of rotation extending from the periphery partway towards the eye of said fan behind said tail blade.

2. In a centrifugal fan, an apertured main vane in two portions curved in the direction of rotation one portion extending from the periphery into the eye of said fan and the other portion set back behind said first portion and extending into the eye of said fan, a tail blade curved contrary to the direction of rotation extending from the periphery and contacting with said first portion of said main vane and located behind the aperture in said main vane, and an intermediate short vane curved in the direction of rotation extending from the periphery partway towards the eye of said fan behind said tail blade.

3. In a centrifugal fan, an apertured main vane in two portions curved in the direction of rotation one portion extending from the periphery into the eye of said fan and the other portion set back behind said first portion and extending into the eye of said fan, a tail blade curved contrary to the direction of rotation extending from the periphery and contacting with said first portion of said main vane and located behind the aperture in said main vane, and an intermediate short vane curved in the direction of rotation extending from the periphery partway towards the eye of said fan behind said tail blade.

4. In a centrifugal fan, an apertured main vane in two portions curved in the direction of rotation one portion extending from the periphery into the eye of said fan and the other portion set back behind said first portion and extending into the eye of said fan, a tail blade curved contrary to the direction of rotation extending from the periphery and contacting with said first portion of said main vane and located behind the aperture in said main vane, and a plurality of intermediate short vanes curved in the direction of rotation extending from the periphery progressively less partway towards the eye of said fan behind said tail blade.

In testimony whereof we have signed our names to this specification.

ROBERT ALFRED BLAKE,
KATHLEEN MARIE DAWES,
(Commonly called CAPELL), Legal Representatives of George Marie Capell, deceased.
